UNITED STATES PATENT OFFICE

PERCY F. STARY, OF DETROIT LAKES, MINNESOTA

HEATER FOR MIXERS FOR CONCRETE AND THE LIKE

Application filed March 6, 1930. Serial No. 433,753.

My invention relates to a commercial mixer for concrete and the like and has for its object the provision of a heater therefor, and to this end, it consists of the novel devices and combinations of devices, hereinafter described and defined in the claims.

The invention in its preferred form is essentially a stove surrounding the drum of a mixer to prevent excessive radiation and cooling of materials when mixing hot batches mainly, bituminous mixes, or to warm the mixer drum and aid in the mixing of any materials in cold weather.

The heater is designed primarily to aid in the mixing of bituminous materials, oils or tar and gavel in cold weather and insure a uniform mix by preventing the cooling of materials while in the mixer with consequent lumping of materials and clogging of the mixer. This heater also keeps the walls of the drum clean as the oil or tar will not stick to the warm walls. The embodiment of the invention in a mixer also materially aids in mixing cement concrete in freezing weather.

The invention may be applied to a mixer as an attachment or it may be built therein and in either case, remains in a constant relative position to the drum, tilts with the drum in tilting mixers, but is not rotatable therewith, and does not interfere with any operation of the mixer either in charging, mixing or discharging.

In the accompanying drawing, which illustrates the invention, like characters indicate like parts throughout the several views.

Referring to the drawing:

Fig. 1 is a fragmentary perspective view of a portable tilting mixer having the invention embodied therein;

Fig. 2 is a view principally in vertical section taken on the line 2-2 of Fig. 1;

Fig. 3 is a view partly in elevation and partly in section taken on the line 3-3 of Fig. 1, some parts being broken away; and

Fig. 4 is a fragmentary view partly in elevation and partly in section showing one of the burners and liquid fuel supply tank.

The commercial mixer, which is of the portable tiltable type, is only fragmentarily illustrated and of the parts thereof shown,

it is important to note the truck frame 5, supporting wheel 6, pedestals 7, supporting yoke 8 journaled in said pedestals for swinging movement in a vertical plane, drum 9, drum ring 10, drum supporting rollers 11 and cooperating thrust roller 12, and engine housing 13. For the purpose of this case, it is not thought necessary to illustrate the engine or driving connections therefrom for rotating the drum and tilting the same except the gear 14 on the ring 10 which forms a part of the driving connections for rotating said drum.

Referring now in detail to the invention, the numeral 15 indicates a sheet steel shell or jacket that fits around the drum 9, has substantially the same contour and is spaced therefrom to leave a hot air chamber 16 therebetween. The heads of the drum 9 loosely project through annular openings in the heads of the shell 15. This shell 15 is rigidly secured to the supporting yoke 8 and held thereby in a constant relative position to the drum 9 for common tilting movement therewith, does not rotate but permits free rotation of the drum 9 therein.

Two commercial oil burners, each of which is indicated as an entirety by the numeral 17, are provided for supplying heat to the drum 9 and the hot air chamber 16. These burners 17 are secured by brackets 18 to the under side of the shell 15 one on each side of the supporting yoke 8 with the necessary air supply. Gasoline or other liquid fuel Z is conveyed to the burners 17 through a pipe 19 having a cut-off valve 20 and which pipe leads from a closed liquid fuel supply tank 21 mounted on the shell 15. This tank 21 has a normally closed filling neck 22 and a pump 23 by the use of which air may be introduced into the tank 21 to keep the fuel Z under the desired pressure for proper feeding to the burners 17. The burners 17 keep the walls of the drum 9 constantly warm while rotating in the air chamber 16, and hence, the contents in the drum.

The above described invention, while intended for use as heretofore stated, is especially well adapted for use on the type of mixer illustrated and used in the mixing of 100

patching materials for bituminous surfaced roadbeds.

What I claim is:

1. In a mixer of the class described, the combination with a drum mounted for rotary and tilting movements, of a jacket for the drum spaced therefrom to leave a hot air chamber therebetween, said jacket being mounted for common tilting movement with the drum and in which the drum is free to rotate in the jacket, a liquid fuel burner mounted to move with the jacket for heating the drum, and a fuel supply tank for the burner mounted on the jacket and having a supply conduit leading to said burner.
2. In a mixer of the class described, the combination with an oscillatory supporting yoke and a drum rotatably mounted thereon, said yoke being operable to move the drum into charging, mixing and discharging positions, of a jacket for the drum spaced therefrom to leave a hot air chamber therebetween, said jacket being rigidly secured to the supporting yoke with the drum free to rotate therein, and a liquid fuel burner for the drum mounted to move with the jacket.
3. In a mixer of the class described, the combination with an oscillatory supporting yoke and a drum rotatably mounted thereon, said yoke being operable to move the drum into charging, mixing and discharging positions, of a jacket for the drum spaced therefrom to leave a hot air chamber therebetween, said jacket being rigidly secured to the supporting yoke with the drum free to rotate therein, a liquid fuel burner for the drum, and a fuel supply tank for the burner having a conduit leading to the burner, said burner and tank being relatively fixed in respect to the jacket.
4. In a mixer of the class described, the combination with an oscillatory supporting yoke and a drum rotatably mounted thereon, said yoke being operable to move the drum into charging, mixing and discharging positions, of a jacket for the drum spaced therefrom to leave a hot air chamber therebetween, said jacket being rigidly secured to the supporting yoke with the drum free to rotate therein, two liquid fuel burners for heating the drum mounted on the bottom of the jacket, one on each side of the supporting yoke, and fuel supply tanks for the burners mounted on the jacket and having a conduit leading to the burners.

In testimony whereof I affix my signature.
PERCY F. STARY.
